CONDIMENT DISPENSER

Theodore M. Reyda, Corning, N.Y., assignor to Corning
Glass Works, Corning, N.Y.

Filed Mar. 19, 1973, Ser. No. 342,760

Term of patent 14 years

Int. Cl. D7—06

U.S. Cl. D7—54

Fig. 1

Fig. 2

FIG. 1 is an elevational view of a condiment dispenser embodying my new design, with the opposite elevational view being identical.

FIG. 2 is a top plan view.

I claim:

The ornamental design for a condiment dispenser, as shown and described.
